UNITED STATES PATENT OFFICE.

ALBERT FRANK, OF NEW YORK, N. Y., ASSIGNOR OF ONE-HALF TO
FARKAS WEISZ, OF NEW YORK, N. Y.

NON-REFILLABLE BOTTLE.

No. 828,395.

Specification of Letters Patent.

Patented Aug. 14, 1906.

Application filed May 28, 1906. Serial No. 319,024.

To all whom it may concern:

Be it known that I, ALBERT FRANK, a subject of the Emperor of Austria-Hungary, residing at New York city, Manhattan, county 5 and State of New York, have invented new and useful Improvements in Non-Refillable Bottles, of which the following is a specification.

This invention relates to a non-refillable 10 bottle provided with a valve-carrying frame which is axially rotatable within the bottle-neck and automatically sets the valve to its operative position whenever the bottle is tilted.

15 In the accompanying drawings, Figure 1 is a longitudinal section through the neck of a bottle embodying my invention and showing the same in an upright position. Fig. 2 is a side view of the valve mechanism, taken 20 at right angles to Fig. 1; Fig. 3, a horizontal section on line 3 3, Fig. 2; Fig. 4, a longitudinal section through the neck, showing the position of the parts when the bottle is tilted; Fig. 5, a section through the valve 25 mechanism, showing the position of the parts when the bottle is placed horizontally; and Fig. 6, a bottom view of the valve-seat.

Within the neck 10 of a bottle is inclosed 30 a tubular bushing composed of an upper sleeve 11 and a lower sleeve 12, between which is fitted a perforated guard 13. To the bottom of sleeve 12 is secured a ring 14, constituting a valve-seat and provided with spring-catches 15, that enter a groove 16 of neck 10, so as to lock the device to the bottle. Between the bushing 11 12 and neck 10 is interposed a cork lining 17, surmounted by a flanged annular top plate 18, fastened to the bushing. A tapering shell 19, supported on 35 guard 13 and engaged by top plate 18, serves for the accommodation of the stopper.

From the center of guard 13 depends a pivot 20, having a head 21. Upon this pivot is free to rotate an L-shaped frame 40 composed of a normally horizontal arm 22 and a normally vertical arm 23. Of these the arm 22 has a hub 24 engaging pivot 20 and carries a counterweight 25 at its free end. The vertical arm 23 is forked, and to its lower end is 45 pivoted at 26 a clack-valve 27, adapted to close against seat 14. This valve is weighted

diametrically opposite its pivot, as at 28. Upon arm 22 is adapted to be supported a curved lever 29, having a centrally-depend- 55 ing lug 30, which is straddled by arm 23 and is pivoted thereto above valve 27, as at 31. The free ends of lever 29 extend to the sides of arm 22 and carry weights 32. From lug 30 depends a finger 33, adapted to engage valve 27 and hold it to its seat 14.

When the bottle is in an upright position, valve 27 will close against seat 14 and lever 29 will be swung down to rest upon arm 22, Fig. 1. When the bottle is tilted, weight 28, coacting with weight 25, will cause frame 22 60 65 23 to turn upon fulcrum 20 axially within the bottle until the weighted or free portion of the valve faces downward. After the valve has assumed this position it will swing outward to permit the escape of the liquid, the 70 lever 29 participating in this movement, Fig. 4. When the bottle is placed in a horizontal position, the lever 29 will be swung inward by weights 32, Fig. 5, and will close valve 27 by finger 33.

75 What I claim is—

1. A non-refillable bottle provided with a weighted frame axially rotatable within the bottle-neck, and with a valve pivoted to said frame, substantially as specified.

80 2. A non-refillable bottle provided with a weighted frame axially rotatable within the bottle-neck, and with a weighted valve pivoted to said frame, substantially as specified.

3. A non-refillable bottle provided with a 85 weighted axially-rotatable frame, a valve and a weighted lever pivoted to the frame, and a finger on the lever that is adapted to engage the valve, substantially as specified.

4. A non-refillable bottle provided with 90 a perforated guard, a pivoted L-shaped weighted frame, a valve and a weighted lever pivoted to the frame, and a finger on the lever which is adapted to engage the valve, substantially as specified.

95 Signed by me at New York city, Manhat- tan, New York, this 26th day of May, 1906.

ALBERT FRANK.
